UNITED STATES PATENT OFFICE.

NAIF J. MALUF, OF HABANA, CUBA.

SIDE-ARM.

1,260,007.

Specification of Letters Patent. Patented Mar. 19, 1918.

Application filed August 25, 1916. Serial No. 116,786.

To all whom it may concern:

Be it known that I, NAIF J. MALUF, a citizen of the Republic of Cuba, residing at Habana, Cuba, have invented new and useful Improvements in Side-Arms, of which the following is a specification.

This invention relates to side-arms, especially to the arms of sharp edges and point, as the saber and sword, although it can be applied to other arms of the same class as the cane-knife, and the object of this invention is to make of these side-arms also a fire-arm by arranging on the cross-head thereof a barrel and shooting mechanism, so that with the same hand that holds the arm of sharp edges and point, by properly placing the thumb, the shooting mechanism can be operated to fire a cartridge in a direction perpendicular to the longitudinal axis of the (last mentioned) arm, which improvement is of great advantage in the equipment of modern army officers, who at present are accustomed to carry the saber in one hand and the pistol in the other, which operation is rather inconvenient since the user must hold the fire-arm with his left hand which is not used for shooting, whereas by this invention the use of the fire and side-arms is reduced to one hand. Another advantage is that the shooting mechanism forming part of this invention is of a simpler and surer construction than that of the repeating fire-arms now in use, offering a greater number of shots. Another object of the invention is to provide an automatic cover for the open end of the barrel of the fire-arm, so that when the arm is not loaded said opening can be kept closed.

In the annexed drawings:—
40 Figure 1 is a side view of a saber provided on its handle with a barrel and mechanism for the firing of bullets, and a magazine for the same.

Fig. 2 is an enlarged side view of the handle of the saber, partially broken away to show the interior of the cartridge magazine.

Fig. 3 is an enlarged front elevation of the saber on its handle with its blade broken away.

Fig. 4 is a sectional view of the saber handle showing the barrel and the shooting mechanism in its position before firing.

Fig. 5 is a view similar to Fig. 4 showing the barrel and the shooting mechanism in its position after firing.

Fig. 6 is a cross-section on line 6—6 of Fig. 2.

Fig. 7 is a detail perspective view of the saber hand-guard. 60

Fig. 8 is a side elevation detail showing the cartridge magazine with its forward wall partially broken away.

Fig. 9 is a front elevation of said cartridge magazine. 65

Fig. 10 is an end view of said cartridge magazine.

Fig. 11 is a transverse vertical section on line 11—11 of Fig. 4.

Fig. 12 is a transverse vertical section on line 12—12 of Fig. 4. 70

Fig. 13 is a transverse vertical section on line 13—13 of Fig. 5.

Fig. 14 is a plan view of the sliding piece which together with the barrel forms the 75 saber cross-head.

Fig. 15 is a horizontal section of the cross-head on line 15—15 of Fig. 2.

Fig. 16 is a detailed vertical longitudinal section on line 16—16 of Fig. 14 showing 80 the mounting of the cover of the barrel's opening, and

Fig. 17 is a front view of said cover.

Supposing a saber having a blade 1, a handle or hilt 2, a hand-guard 3 and the 85 cross-head 4, the invention consists in constructing the saber so that the cross-head 4 may be formed by the barrel and slider of a repeating fire-arm and the handle or hilt 2 may be formed by the cartridge magazine 90 of said fire arm without the saber losing its shape. The handle or hilt 2 is formed by a frame in the form of a casing which is open at its side and ends, on one of which sides fits the extension 1' of the saber blade 1, 95 the same being secured in position by the engagement of its point in a recess 6 formed in a side of the lower end of frame 2 and by means of a screw 7 which fixes it to the cross-piece 5 of said frame and a head pin 100 projecting laterally from the frame and which fits in a notch 9 formed on the side portion of blade 1. Frame 2 is covered on its sides with two shells 10 which are fixed on the sides of said frame by means 105 of spring members 11 projecting from the inner faces of said shells and fitting in small recesses with narrow entrance apertures 12 formed in the sides of frame 2.

Hand-guard 3 is attached by a projection 110 13 on its lower end to a side of frame 2, and it has on its upper portion a plane setting

14 provided on its inner end with two small pins 15, this setting being followed with an opened space 16 which is closed on one side by the fixed portion of hand-guard 3 and on the other side by a movable member 17 hinged at 17' on a side of the plane setting 14 and which has on its inner part a revolving bolt 18 which fits laterally on one of the shells 10, so as to fix in position the 10 hand-guard 3 on the handle or hilt 2, and for the same purpose the opposite fixed part of hand-guard 3 has inside thereof a pin 19 actuated by a spring and which projects on its inner side and fits in a corresponding 15 aperture of shell 10 of handle 2.

The plane portion 14 of hand-guard 3 serves as a setting for the front frame 4' of the sliding piece 4, which latter forms the cross-head of the saber and is disposed 20 in the open space 16 of hand-guard 3, there being located within frame 4' the barrel 20, which has a lower projecting portion 21 which has in its front a cylindrical recess 22 in which a helical compression spring 23 25 is inserted. This spring is seated at its rear end against the portion 21 of barrel 20 with the other end bearing against the inner side of the front part of frame 4' of the sliding piece, said spring surrounding 30 a pin 24 projecting from the latter, and said spring 23 is located in a recess formed between an upper channel 20' in the barrel and a lower channel 21' in the bottom of frame 4' (Fig. 11), the small pins 15 of 35 the plane setting 14 entering in apertures 25 formed in the lower edge of recess 22. The sliding piece 4 is guided in its movements to and from the barrel by means of ribs 26 which the latter has on its sides and 40 on which slide grooves 27 formed in the inner face of the sides of frame 4' and also by inner edges 65 projecting from the side walls of sliding piece 4 and sliding in grooves 66 formed in the upper edges of 45 the side walls of frame 2 of the handle or hilt (Fig. 13).

The sliding piece 4 is closed at its top, and ends at its rear portion in an extension of curved form 4" which serves the same 50 purpose as the rear end of the cross-head of the side arms, and said sliding piece is channeled in its bottom in order to slide on the upper end of the cartridge magazine which will be described later. In the inner 55 part of the sliding piece 4, there is mounted in a longitudinal passage 28 a sliding block 29 which carries on its front end the striker 30 which is surrounded by a helical compression spring 31. This spring bears at 60 one end on a shoulder 32 formed in said longitudinal passage 28 and at the other end against the block 29, the travel of the block 29 being limited by means of a pin 33 projecting to the interior of the passage 28 and 65 into a cavity 34 formed in the lower part of

block 29; and in the upper part of said sliding piece 4 there is pivoted on a pin 35, against the tension of a helical spring 36 located in a small socket 37, an angular shaped pawl 38, which is partially disposed 70 in a longitudinal angular-shaped groove 39 formed at the top and front of the sliding piece 4.

The cartridges 40 are fed from a magazine 41 of similar construction to that of the magazines used at present in repeating fire arms, it being provided with a zigzag shaped spring 42 fixed to the end cover 43, which has an end adapted to be grasped by the fingers and at its free end said spring carries an angular follower plate 44 on which lies the last cartridge 40. The cover 43 has in the outer portion of the casing forming the magazine 41, a latch 45 projecting inwardly, which serves to secure the magazine to the frame 4, entering in a corresponding cavity formed in the end of said frame. This cartridge magazine 40 is lodged in frame 2 fitting on the sides thereof, the latter forming channels 2' that guide the 85 magazine (Fig. 6) and the end edges of the side walls of said magazine engage in lateral grooves 46 formed in the lower central portion of the slider 4 (Fig. 13) in order to guide the slide in its reciprocating movements, the solid portion of the slider 4 that is under the longitudinal passage 28, remaining directly on the rear of the first cartridge 40 of the magazine for the purpose that will be explained hereinafter. 90

The mechanism that operates the striker 30 consists of a push button 47 having a slightly concave face for inserting the finger when it is to be pressed, and which button is mounted in a cavity 48 formed in the 105 upper wider front portion of frame 2 of the handle or hilt, and to the inner part of this button is articulated a link 49 which traverses frame 2 from one to the other side, passing out and over a side of magazine 41, and which link is pivoted at the other end to a small lever 50 pivoted on pin 51 on the inner face of the side wall of frame 2 in a chamber formed in the upper rear portion of said frame 2. The end of this small 110 lever 50 engages a shoulder of a hammer 52 pivoted on a pin 53 inside of said frame 2, a projecting hook-shaped portion 52' of said hammer being caught by the curved end of a spring 54 which is secured at its 115 other end in the frame 2 by means of a screw 55.

The open end of the barrel 20 is closed, when the fire arm is not being used, by means of a locking plate 56, which is pivoted on the lower portion of the end face of the barrel 20 by means of a screw 58 against the elastic twisting of a helical spring 59 surrounding said screw and located in a cavity 60 formed at the end of barrel 20, 120

and said cover plate 56 has an opening 61 to register with the bore of the barrel 20 and a point 62 to project from the upper part of the barrel and to serve as a sight, 5 each end of said cover plate 66 being provided with an opening 63 into which can project a small stem 64 projecting from the lower part of the front portion of front frame 4' of the sliding piece 4. In normal 10 conditions the cover plate 56 is secured by the small stem 64 which enters in the opening 63 adjacent to point 62, the bore of barrel 20 being closed by the solid part of plate 56.

15 The operation of the repeating fire-arm adapted to the saber is as follows:—The sliding piece 4 being in its closed position and the cartridge magazine inserted in the handle or hilt 2, it is necessary, to load the 20 fire-arm, to pull back the sliding piece by catching the raised stem 4" thereof, whereupon, in the first place, on the withdrawal of the small pin 64 from the opening 63 adjacent to point 62 of the coverplate 56 25 the latter rotates on its pivot by the action of the helical spring 59 giving half a turn and remaining so that the opening 61 may register with the bore of barrel 20, and in the second place, the first cartridge 40 of 30 the magazine 41 which was held by the central lower portion of the sliding piece 4, on being freed by the rearward movement of said sliding piece, rises up enough to place itself partly in front of the central lower portion of said sliding piece under influence 35 of the lifting force exerted by spring 42 of magazine 41, in which position the base of cartridge 40 is caught by pawl 38 at the same time that hammer 52 is slightly pressed 40 backwardly by the same central portion of said sliding piece 4. When the sliding piece advances again under the action of spring 23, the central lower portion of the sliding piece 4 pushes the first cartridge 40, introducing it into the chamber of barrel 20, the base of the shell of said cartridge 40 being still held by the angular pawl 38, as shown 45 in Fig. 4 of the drawings. Now, by inwardly pressing the button 47, the small 50 lever 50 is actuated and its free end releases the hammer 52 which by the tension of spring 54 is oscillated on its pivot 53 and impinges against block 29 of the striker 30 thus occasioning the striking thereof on the 55 cartridge cap, producing the shot. At this time the expansive force of the gases formed by the explosion of the cartridge drives back the sliding piece 4, but on backward movement of the central lower part of this 60 slider, which held in position the first cartridge of the magazine, 41, it releases this cartridge, which rises up under the action of spring 42, and since at the same time 65 the cartridge shell 40 of the shot fired has returned back with sliding piece 4, which

latter is holding it on its base by the angular pawl 38, the base of said shell hits against the new cartridge coming from magazine 41, and it is thrown out through frame 4' once the angular pawl 38 has released the shell, which occurs on being slightly raised by the same shell when this is pushed by the coming cartridge. Immediately thereafter, by the action of spring 23 the sliding piece 4 advances again to the 75 barrel 20, the cartridge 40, which is the last one in the magazine, being pushed by the central lower part of sliding piece 4 and inserted in the chamber of barrel 20, the hammer 52 having now returned to its firing 80 position by the backward oscillation of the upper part thereof caused by the same central lower portion of sliding piece 4, so that when the hammer is released on the new advance of the sliding piece 4, the same is 85 locked by the end of the small lever 50 in position to fire a new shot by inwardly pushing the button 47.

This firing mechanism has the advantage over the ones now in use of being safer in 90 its handling since the button or trigger 47 is normally contained wholly in its cavity, it being impossible therefore for the arm to discharge accidentally.

It is obvious that the form of the pieces 95 comprising the repeating mechanism for the shooting of cartridges can be slightly varied or changed, as can also be varied the cartridge magazine adapting it to the form of any side arm desired, without altering 100 the spirit of the invention which is as pointed out in the following claims.

What I claim is:—

1. A combined cutting and firing side-arm comprising a common handle, a cutting 105 blade projecting from the handle, and a firearm provided on the handle at the base of the said blade, the said firearm consisting of firing mechanism and a top part disposed so as to constitute a cross-guard and 110 including a barrel provided with inclined upper deflecting surfaces which slope from the said blade to the muzzle of the barrel.

2. A combined cutting and firing side-arm comprising a common handle, a cutting 115 blade projecting from the handle, and a firearm provided on the handle at the base of the said blade, the said firearm consisting of firing mechanism a top part disposed so as to constitute a cross-guard and including 120 a barrel provided with inclined upper, deflecting surfaces which slope from the said blade to the muzzle of the barrel, and an adjustable sight provided at the muzzle and adapted to project above the barrel in operative position or to be withdrawn below the 125 said deflecting surfaces into inoperative position.

3. A firearm comprising a barrel, firing mechanism associated with the barrel, a 130

movable closure member mounted at the muzzle of the barrel and having a front sight thereon, the arrangement being such that the said member is adapted, in its operative position, to close the said muzzle and, in inoperative position, to free the muzzle and to hold the front sight in operative position above the barrel.

4. A firearm comprising a barrel, firing mechanism associated with the barrel, a movable closure member mounted at the muzzle of the barrel and having a front sight thereon, the arrangement being such that the said member is adapted, in its operative position, to close the said muzzle and, in inoperative position, to free the muzzle and to hold the front sight in operative position above the barrel, resilient means tending normally to maintain the said closure member in inoperative position, means for cocking the firing mechanism, and means associated with the cocking means for securing the said closure member in adjusted po-

sition and adapted to release the latter during cocking of the firing mechanism. 25

5. A firearm comprising a frame, a barrel mounted on the frame, the said frame being provided with a trigger-receiving cavity at a suitable position, and firing mechanism associated with the barrel and including a hammer, a spring for the hammer, releasable means for locking the hammer in cocked position, a trigger mounted movably in said frame cavity, and means connecting the trigger operatively with the said locking means and adapted to cause the trigger to project from the frame cavity only when the hammer is cocked.

In testimony whereof I have signed my name to this specification in the presence of 40 two subscribing witnesses.

NAIF J. MALUF.
